UNITED STATES PATENT OFFICE

GRAHAM CHARLES PEARSE CHUBB, WILLIAM ELLIS COLMER, AND ALBERT RICHARD BANNISTER, OF LONDON, ENGLAND, ASSIGNEES TO THE BELL PUNCH AND PRINTING COMPANY LIMITED, OF UXBRIDGE, ENGLAND

TICKET ISSUING MACHINE

Application filed April 25, 1932, Serial No. 607,468, and in Great Britain May 8, 1931.

This invention relates to machines for issuing tickets from a strip of web and of the type in which a rotary feed drum driven by means of a Maltese-cross or Geneva mechanism, is provided upon its periphery at regular intervals with pins arranged to extend through holes formed in the ticket strip or web so as to feed the web when the drum rotates, and a knife, actuated at the completion of each revolution of the pin-wheel of the Geneva mechanism, is arranged to cut off the individual tickets from the web.

According to this invention there is provided a ticket issuing machine of the type described which comprises means operable manually to control the operation of an electric motor and the operative connection thereof to the ticket issuing mechanism in such a manner as to ensure the delivery of a predetermined number of tickets.

The machine may be provided, for example, with a bank of key levers serving respectively for the issue of one, two, three or more tickets from the machine, and two or more ticket issuing mechanisms may be grouped for operation by a single motor to form one machine, each mechanism being provided with a key lever or bank of key levers so that tickets of different denominations may be issued from the machine.

In order that the invention may be fully understood, reference is directed to the accompanying drawings, in which:

Figure 1 is a vertical side elevation of a ticket issuing machine constructed in accordance with this invention, and with the casing shown in section.

Figure 2 is a plan of Figure 1 with the casing shown in section.

Figure 3 is a section on the line 3-3 of Figure 2.

Figure 4 is a section on the line 4-4 of Figure 2, but with some of the parts of the mechanism illustrated in a different position,

and

Figure 5 is a view similar to Figure 4, but with parts of the mechanism illustrated in a still further different position.

Referring to Figures 1 to 3, a pair of ticket issuing mechanisms, A, B, are grouped to-

gether for operation by a single electric motor C and are housed therewith in a casing D. Each ticket issuing mechanism comprises a bank of keys 1, 2, 3, 4, 5 pivotally mounted at 6 to the frame 7 of the mechanism and maintained in a normally raised position by springs 8. Each key lever is provided with a heel 9, finger 10 and differential abutment 11, the heels 9 and fingers 10 respectively of each of the keys being normally aligned with one another. The free ends of the fingers 10 are located beneath one arm 12 of a double-armed trigger lever pivotally mounted at 13 to the frame 7. The other arm 14 of the trigger lever extends over a pin 15 provided upon a detent pawl 16 also pivotally mounted at 13 and arranged to co-operate with ratchet teeth 17 formed in a plunger 18 which is slidably mounted in a guide 19 provided upon the frame 7. The plunger 18 is maintained against rotation by a pin 18a thereon extending into a guide slot 19a on the guide 19. The end of the plunger 18 disposed adjacent to the key levers is provided with a cross-head 20 and a compression spring 21 is located between the said cross-head and the adjacent end of the guide 19 and normally tends to move the cross-head and plunger towards the key levers from the position shown in Figure 1. A latching or return pawl 22 is arranged to extend through a slot 23 formed in the guide 19 and to co-operate with the teeth 17 of the plunger 18, the said return pawl being operatively connected to an eccentric 24 provided at one end of a lay-shaft 25 rotatably mounted in bearings in the frame 7. A tension spring 26 operatively connects the pawls 16 and 22 together at points located below the pivot 13 and the eccentric 24, and thus tends to maintain the said pawls in engagement with the teeth 17. The finger 14 of the trigger lever is arranged to extend over a pin 27 provided upon the pawl 22. The pawl 16 normally maintains the plunger 18 in the position indicated in Figures 1 and 2 with the said plunger abutting against an adjustable tappet 28 provided upon one arm of a bell crank lever 28a mounted upon a vertically disposed pivot 29. The other

- arm of the bell crank lever is in the form of a fork 30 normally bearing against one end of a sleeve 31 slidably mounted upon a driving spindle 32 rotatably carried in bearings 33. The sleeve 31 is keyed so as to rotate with the spindle 32 by means of a pin and slot connection 34 and carries a gear wheel 35 at one end. With the parts of the mechanism illustrated in the positions indicated in Figures 1 and 2, the gear wheel 35 is maintained, against the pressure of a spring 36, out of mesh with a secondary wheel 37 keyed to one end of the layshaft 25.
- The layshaft 25 is provided with a second gear wheel 38 arranged in mesh with a similar gear wheel 39 keyed to and rotatable with a pin-wheel 40 of a Geneva mechanism 40, 41. The Geneva mechanism is operatively connected to a spindle 42 carried in bearings in the frame 7 and upon which a feed drum 43 is keyed. The feed drum 43 is provided around its periphery with pins 44 operable to extend through holes equally spaced along the length of a preprinted ticket web (not shown) so that when the drum is rotated in the direction of the arrow *a*, the free end of the web is passed through the slot 45 and into engagement with an inclined guide plate 46 secured to the upper panel of the casing D for a purpose hereinafter described. It will be appreciated that one rotation of the pin-wheel 40 effects the delivery of one ticket length of the web through the slot 45.
- A knife 47 is carried upon one end of a U-shaped frame 48, the limbs of which are pivotally mounted at 49 to the frame of the mechanism and one of the said limbs is provided with an arm 50, Figure 3, the free end of which is connected by means of a link 51 to a crank pin 52 provided upon the gear wheel 37, a tension spring 53 being connected between the link 51 and an anchorage 54 on the frame 7 for a purpose hereinafter described.
- The main driving spindle 32 is operatively connected by worm gearing to the driving motor C, the said gearing being housed within a casing 55.
- A mercury interrupter switch 56 is carried at one end of a spindle 57 rotatably mounted in bearings formed in the brackets of the bearings 33. The interrupter switch is operatively connected in the circuit of the motor C and is arranged to be normally maintained in an "off" position as shown in Figures 1, 2, 3 and 4, for example, by means of a spring, not shown, or under the influence of gravity. The spindle 57 is provided with a pair of arms 58, each of which normally bears against an extension 59 of the fork 30 of one of the bell crank levers 28a, the arrangement being such that a rotation of the bell crank lever about its pivot 29 in a clockwise direction, Figure 2, causes the extension 59 to move the corresponding arm 58 and rock the spindle 57,

thus moving the interrupter switch 56 into the "on" position shown in Figure 5.

A second adjustable tappet 60 similar to the tappet 28 is provided upon the aforesaid bell crank lever 28a and is arranged to co-operate with one end of a slidably mounted plunger 61 provided with a cross-head 62 located adjacent to the heels 9 of the group of key levers 1 to 5.

The operation of the mechanism is as follows:—

With parts of the mechanism A and B in the position illustrated in Figures 1 to 3, and assuming that it is required to deliver five tickets from the mechanism B, the key lever 5 is depressed so that the finger 10 rocks the trigger lever 12, 14 into the position illustrated in Figure 4, so that the arm 14 thereof engages with the pins 15, 27 and disengages the pawls 16 and 22 from the teeth 17 of the plunger 18. The spring 21 thereupon moves the said plunger 18 and the cross head 20 towards the key levers, and the differential abutment 11 of the depressed key lever arrests the movement of the plunger 18, the movement corresponding to a number of the teeth 17 equal to the number of tickets required, and the abutments 11 of the undepressed keys 1 to 4 being located out of the path of movement of the said cross-head. In the depressed position of the key lever 5, the heel 9 thereof abuts against the cross-head 62 and maintains the plunger 61 in engagement with the tappet 60 so that the forked arm 30 of the corresponding bell crank lever maintains the sleeve 31 in the position illustrated in Figure 2 against the pressure of the spring 36. Upon release of the depressed key lever 5 the pawls 16, 22 are moved into engagement with the teeth 17 of the plunger 18 by the spring 26 and simultaneously the spring 36 moves the sleeve 31 in the direction of the arrow *b*, Figure 2, and establishes an operative connection between the corresponding gear wheels 35 and 37, the edges of the teeth of the said wheels preferably being bevelled to assist such engagement. The accompanying clockwise movement of the forked arm 30 of the corresponding bell crank lever 28a causes the extension 59 thereof to rock the spindle 57 and move the interrupted switch 56 to the "on" position and thereby close the circuit of the motor C. The motor thereupon drives the spindle 32 and the ticket issuing mechanism. With each effective operation of the Geneva mechanism 40, 41, to deliver a ticket the pawl 22 is reciprocated and effects a return movement of the plunger 18 towards the normal position against the pressure of the spring 21, by an amount corresponding to one of the teeth 17. In the present instance, at the completion of the delivery of the fifth successive ticket the pawl 22 moves the plunger 18 into engagement with the tappet 28 and rocks the corresponding bell crank lever 28a 180

so that the forked arm 30 thereof moves the corresponding sleeve 31 to disengage the gear wheel 35 from the gear wheel 37, whilst, at the same time, the accompanying movement 5 of the extension 59 causes the interrupter switch 56 to be returned to the normal or "off" position.

It will be appreciated that during each revolution of the gear wheel 37, the U-shaped 10 frame 48 is oscillated with the knife 47 and effects the severance of each ticket delivered.

The spring 53 is so arranged that it is tensioned during the initial rotation of the gear wheel 37 and thereafter acts to assist the rotation 15 of the said gear wheel 37 during the final portion of each revolution thereof, thus reducing the degree of frictional engagement between the teeth of the said gear wheel 37 and the teeth of the wheel 35. This action 20 facilitates the disengagement of the wheel 35 from the wheel 37.

It will be observed that if any other of the keys 1 to 5 should be depressed, the resulting movement of the plunger 18 is limited by the 25 differential abutment 11 of the key operated which is caused to extend into the path of movement of the cross-head 20 and this movement corresponds to a number of the teeth 17 equal to the number of tickets it is 30 required to deliver. The pawls 16 and 22 are arranged to re-engage with the teeth 17 before the abutment 11 is moved clear of the cross-head 20 during the return movement of the depressed key and the plunger 18 is always 35 returned to the normal position by the pawl 22 when the requisite number of tickets have been delivered.

As each ticket is delivered through the slot 45 it is deflected by the guide 46 and there- 40 after raises a spring controlled flap 63 so that the leading edge of the ticket extends through a delivery slot 64 formed in the upper panel of the casing D of the machine, the ticket being severed before the delivery of the 45 next successive ticket commences. As soon as the next ticket raises the flap 63 the frictional engagement between the two tickets effected by the pressure of the flap causes them to be moved along the guide 46 together, 50 so that the ticket first delivered extends in advance of the ticket being delivered. This action is repeated during the delivery of successive tickets, so that all the tickets are 55 maintained in position by the flap 63 with their leading edges equally displaced relatively to one another so that the number of tickets may be readily checked both by the operator and by the purchaser before being 60 removed from the machine.

It will be appreciated that any number of ticket delivery mechanisms such as A and B may be grouped together in the manner above described so as to be driven by a single 65 electric motor.

What we claim and desire to secure by Letters Patent is:—

1. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor and manually operable selector devices adapted to control the circuit of said motor and couple the same in driving relationship to said Geneva mechanism to deliver one or a plurality of tickets solely in accordance with the manually operable device selected. 70

2. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a switch for the circuit of said motor, gear mechanism adapted to couple said motor to said Geneva mechanism and normally uncoupled, manually operable selector devices operatively 85 connected to said gear mechanism and adapted upon operation to actuate the same and couple said motor, an operative connection between said switch and all said selector devices so that said switch is closed only after 90 said motor is coupled and means operable automatically to actuate said gear mechanism and uncouple said motor and open said switch when the delivery of a number of tickets has been effected in accordance with the manually operable device selected. 100

3. A ticket issuing machine which comprises in combination a rotary feed drum provided with peripheral pins adapted to extend through holes formed in a ticket strip whereby rotation of the said drum feeds said strip, a Geneva mechanism operatively connected to said drum and operable upon each actuation to rotate said drum and feed one ticket from the machine, an electric motor, a 110 switch for the circuit of said motor, gear mechanism operable slidably to couple said motor to said Geneva mechanism and normally uncoupled, manually operable selector devices operatively connected to said gear mechanism and adapted upon operation to actuate the same and couple said motor, an operative connection between said switch and all said selector devices so that said switch is closed only after 115 said motor is coupled, means operable automatically to actuate said gear mechanism and uncouple said motor and open said switch when the delivery of a number of tickets has been effected in accordance with the manually operable device selected. 120

125

- lected, and yielding means operable to reduce the frictional engagement between the slidably operable members of said gear mechanism so as to facilitate the uncoupling thereof.
4. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a manually operable selector devices adapted to control the circuit of said motor and couple the same in driving relationship to said Geneva mechanism and a counting-out device controlled by said selector devices and operable automatically in synchronism with said Geneva mechanism so as to uncouple said motor when the delivery of a number of tickets has been effected in accordance with the manually operable device selected.
5. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a switch for the circuit of said motor, gear mechanism adapted to couple said motor to said Geneva mechanism and normally uncoupled, manually operable selector devices operatively connected to said gear mechanism and adapted upon operation to actuate the same and couple said motor, an operative connection between said switch and all said selector devices so that said switch is closed only after said motor is coupled and a counting-out device controlled by said selector devices and operable automatically in synchronism with said Geneva mechanism so as to uncouple said motor and open said switch when the delivery of a number of tickets has been effected in accordance with the manually operable device selected.
6. A ticket issuing machine which comprises in combination a rotary feed drum provided with peripheral pins adapted to extend through holes formed in a ticket strip whereby rotation of said drum feeds said strip, a Geneva mechanism operatively connected to said drum operable upon each actuation to rotate said drum and feed one ticket from the machine, an electric motor, a switch for the circuit of said motor, gear mechanism operable slidably to couple said motor to said Geneva mechanism and normally uncoupled, manually operable selector devices operatively connected to said gear mechanism and adapted upon operation to actuate the same and couple said motor to said Geneva mechanism so that said switch is closed only after said motor is coupled, a counting-out device controlled by said selector devices and operable automatically in synchronism with said Geneva mechanism so as to uncouple said motor and open said switch when the delivery of a number of tickets has been effected in accordance with the manually operable device selected.
7. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor and a plurality of selector keys adapted to control the circuit of said motor and couple the same in driving relationship to said Geneva mechanism to deliver one or a plurality of tickets solely in accordance with the key selected.
8. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a switch for the circuit of said motor, gear mechanism adapted to couple said motor to said Geneva mechanism and normally uncoupled, a plurality of selector keys operatively connected to said gear mechanism and adapted upon operation to actuate the same and couple said motor, an operative connection between said switch and all said keys so that said switch is closed only after said motor is coupled and means operable automatically to actuate said gear mechanism and uncouple said motor and open said switch when the delivery of a number of tickets has been effected in accordance with the key selected.
9. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a switch for the circuit of said motor, gear mechanism operable slidably to couple said motor to said Geneva mechanism so that said switch is closed only after said motor is coupled, a counting-out device controlled by said selector devices and operable automatically in synchronism with said Geneva mechanism so as to uncouple said motor and open said switch when the delivery of a number of tickets has been effected in accordance with the manually operable device selected.

- motor to said Geneva mechanism and normally uncoupled, a plurality of selector keys operatively connected to said gear mechanism and adapted upon the operation of any key 5 to actuate said gear and couple said motor, an operative connection between said switch and all said keys so that said switch is closed only after said motor is coupled, means operable automatically to actuate said gear mechanism and uncouple said motor and open said switch when the delivery of a number of tickets has been effected in accordance with the key selected, and yielding means operable to reduce the frictional engagement 10 between the slidably operable members of said gear mechanism so as to facilitate the uncoupling thereof.
10. A ticket issuing machine which comprises in combination a rotary feed drum 20 provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a plurality of selector keys adapted to control the circuit of said motor and couple the same in driving relationship to said Geneva mechanism and a counting-out device controlled by any of said keys and operable automatically in synchronism with said Geneva mechanism so as to uncouple said motor when the delivery of a number of tickets has been effected in accordance with the key selected. 30
11. A ticket issuing machine which comprises in combination a rotary feed drum provided with peripheral pins adapted to extend through holes formed in a ticket strip 40 whereby rotation of said drum feeds said strip, a Geneva mechanism operatively connected to said drum and operable upon each actuation to rotate said drum and feed one ticket from the machine, an electric motor, a switch for the circuit of said motor, gear mechanism adapted to couple said motor to said Geneva mechanism and normally uncoupled, a plurality of selector keys operatively connected to said gear mechanism and adapted upon the operation of any key to 50 actuate said gear and couple said motor, an operative connection between said switch and all said keys so that said switch is closed only after said motor is coupled and a counting-out device controlled by any of said keys and operable automatically in synchronism with said Geneva mechanism so as to uncouple said motor and open said switch when the delivery of a number of tickets has been effected in accordance with the key selected. 60
12. A ticket issuing machine which comprises in combination a rotary feed drum provided with peripheral pins adapted to extend through holes formed in a ticket strip 65 whereby rotation of said drum feeds said
- strip, a Geneva mechanism operatively connected to said drum operable upon each actuation to rotate said drum and feed one ticket from the machine, an electric motor, a mercury interrupter switch for the circuit of 70 said motor, gear mechanism operable slidably to couple said motor to said Geneva mechanism and normally uncoupled, a plurality of selector keys operatively connected to said gear mechanism and adapted upon operation to actuate the same and couple said motor, an operative connection between said switch and all said selector devices so that said switch is tilted and closed only after said motor is coupled, a counting-out device 75 controlled by any of said keys and operable automatically in synchronism with said Geneva mechanism so as to uncouple said motor and tilt and open said switch when the delivery of a number of tickets has been effected in accordance with the key selected, and yielding means operable to reduce the frictional engagement between the slidably operable members of said gear mechanism so as to facilitate the uncoupling thereof. 80
13. A ticket issuing machine which comprises in combination a rotary feed drum provided with peripheral pins adapted to extend through holes formed in a ticket strip 85 whereby rotation of said drum feeds said strip, a Geneva mechanism operatively connected to said drum and operable upon each actuation to rotate said drum and feed one ticket from the machine, an electric motor, a switch for the circuit of said motor, gear mechanism adapted to couple said motor to said Geneva mechanism and normally uncoupled, a normally locked toothed ratchet member operatively connected to said gear mechanism and operable to be moved in one direction from the locked position by a yielding control to effect an actuation of said gear to couple said motor and movable thereafter in the opposite direction by a pawl coupled to said Geneva mechanism a unitary 90 amount for each ticket delivered and finally to actuate said gear and uncouple said motor, a plurality of selector keys each operable to unlock said ratchet member, differential abutment mechanism controlled by said 95 keys and operable to limit the extent of movement of said ratchet member by said yielding control an amount equal to one or a plurality of said unitary amounts in accordance with the key operated, and an operative connection between the motor switch and the gear mechanism operable to close said switch after the motor is coupled by the gear mechanism and to open the switch when the number of tickets corresponding to the key selected have been delivered. 100
14. In a ticket issuing machine the combination with an electric motor and a main driving shaft coupled thereto, of a plurality of ticket issuing units each comprising a ro- 105

- 130

- 5 tary feed drum provided with peripheral pins adapted to extend through holes formed in a ticket strip whereby rotation of said drum feeds said strip, a Geneva mechanism 5 operatively connected to said drum and operable upon each actuation to rotate said drum and feed one ticket from the machine, and manually operable selector devices adapted to control the circuit of said electric motor and 10 couple the driving shaft to said Geneva mechanism to deliver one or a plurality of tickets solely in accordance with the manually operable device selected.
- 15 15. In a ticket issuing machine the combination with an electric motor, a switch for the circuit thereof and a main driving shaft coupled to the motor, of a plurality of ticket issuing units each comprising a rotary feed drum provided with peripheral pins adapted 20 to extend through holes formed in a ticket strip whereby rotation of said drum feeds said strip, a Geneva mechanism operatively connected to said drum and operable upon each actuation to rotate said drum and feed 25 one ticket from the machine, gear mechanism adapted to couple said driving shaft to said Geneva mechanism and normally uncoupled, manually operable selector devices 30 operatively connected to said gear mechanism and adapted upon operation to couple the same, an operative connection between said switch and all said selector devices so that said switch is closed only after said gear mechanism is coupled and means operable 35 automatically to uncouple said gear mechanism and open said switch when the delivery of a number of tickets has been effected in accordance with the manually operable device selected.
- 40 16. In a ticket issuing machine the combination with an electric motor, a switch for the circuit thereof and a main driving shaft coupled to the motor, of a plurality of ticket issuing units each comprising a rotary feed drum provided with peripheral pins adapted 45 to extend through holes formed in a ticket strip whereby rotation of said drum feeds said strip, a Geneva mechanism operatively connected to said drum and operable upon each actuation to rotate said drum and feed 50 one ticket from the machine, gear mechanism operable slidably to couple said driving shaft to said Geneva mechanism and normally uncoupled, manually operable selector devices 55 operatively connected to said gear mechanism and adapted upon operation to couple the same, an operative connection between said switch and all said selector devices so that said switch is closed only after said gear mechanism is coupled, means operable 60 automatically to uncouple said gear mechanism and open said switch when the delivery of a number of tickets has been effected in accordance with the manually operable device selected, and yielding means operable to 65

duce the frictional engagement between the slidably operable members of said gear mechanism so as to facilitate the uncoupling thereof.

17. In a ticket issuing machine the combination with an electric motor and a main driving shaft coupled thereto, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, manually operable selector devices adapted to control the circuit of said electric motor and couple the driving shaft to said Geneva mechanism and a counting-out device controlled by said selector devices and operable automatically in synchronism with said Geneva mechanism so as to uncouple said driving shaft when the delivery of a number of tickets has been effected in accordance with the manually operable device selected. 70 75 80 85 90

18. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, gear mechanism adapted to couple said driving shaft to said Geneva mechanism and normally uncoupled, manually operable selector devices 100 operatively connected to said gear mechanism and adapted upon operation to couple the same, an operative connection between said switch and all said selector devices so that said switch is closed only after said gear mechanism is coupled and a counting-out device controlled by said selector devices and operable automatically in synchronism with said Geneva mechanism so as to uncouple said gear mechanism and open said switch 105 when the delivery of a number of tickets has been effected in accordance with the manually operable device selected. 110 115

19. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum operable upon each actuation to rotate said drum and feed one ticket from the machine, gear mechanism 120 125 130

operable slidably to couple said driving shaft to said Geneva mechanism and normally uncoupled, manually operable selector devices operatively connected to said gear mechanism and adapted upon operation to actuate the same and couple said driving shaft, an operative connection between said switch and all said selector devices so that said switch is closed only after said driving shaft is coupled, a counting-out device controlled by said selector devices and operable automatically in synchronism with said Geneva mechanism so as to open said switch and uncouple said driving shaft when the delivery of a number of tickets has been effected in accordance with the manually operable device selected and yielding means operable to reduce the frictional engagement between the slidably operable members of said gear mechanism so as to facilitate the uncoupling thereof.

20. In a ticket issuing machine the combination with an electric motor and a main driving shaft coupled thereto, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, and a plurality of selector keys adapted to control the circuit of said motor and couple said driving shaft to said Geneva mechanism to deliver one or a plurality of tickets solely in accordance with the key selected.

21. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, gear mechanism adapted to couple said driving shaft to said Geneva mechanism and normally uncoupled, a plurality of selector keys operatively connected to said gear mechanism and adapted upon operation to actuate the same and couple said gear mechanism, an operative connection between said switch and all said keys so that said switch is closed only after said gear mechanism is coupled and means operable automatically to actuate said gear mechanism and uncouple said driving shaft and open said switch when the delivery of a number of tickets has been effected in accordance with the key selected.

22. In a ticket issuing machine the combination with an electric motor, a switch for

the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, gear mechanism operable slidably to couple said driving shaft to said Geneva mechanism and normally uncoupled, a plurality of selector keys operatively connected to said gear mechanism and adapted upon the operation of any key to couple said gear, an operative connection between said

23. In a ticket issuing machine the combination with an electric motor and a main driving shaft coupled thereto, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, a plurality of selector keys adapted to control the circuit of said motor and couple said driving shaft to said Geneva mechanism to deliver one or a plurality of tickets solely in accordance with the key selected.

24. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, gear mechanism adapted to couple said driving shaft to said Geneva mechanism and normally uncoupled, a plurality of selector keys operatively connected to said gear mechanism and adapted upon the operation of any key to couple said

- switch and all said keys so that said switch is closed only after said gear mechanism is coupled and a counting-out device controlled by any of said keys and operable automatically in synchronism with said Geneva mechanism so as to uncouple said gear mechanism and open said switch when the delivery of a number of tickets has been effected in accordance with the key selected.

25. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum operable upon each actuation to rotate said drum and feed one ticket from the machine, gear mechanism operable slidably to couple said driving shaft to said Geneva mechanism and normally uncoupled, a plurality of selector keys operatively connected to said gear mechanism and adapted upon operation to couple the same, an operative connection between said switch and all said selector devices so that said switch is closed only after said gear mechanism is coupled, a counting-out device controlled by any of said keys and operable automatically in synchronism with said Geneva mechanism so as to uncouple said gear mechanism and open said switch when the delivery of a number of tickets has been effected in accordance with the key selected, and yielding means operable to reduce the frictional engagement between the slidably operable members of said gear mechanism so as to facilitate the uncoupling thereof.

26. In a ticket issuing machine the combination with an electric motor, a switch for the circuit thereof and a main driving shaft coupled to the motor, of a plurality of ticket issuing units each comprising a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, gear mechanism adapted to couple said driving shaft to said Geneva mechanism and normally uncoupled, a normally locked toothed ratchet member operatively connected to said gear mechanism and operable to be moved in one direction from the locked position by a yielding control to effect coupling of said gear and movable thereafter in the opposite direction by a pawl operatively connected to said Geneva mechanism a unitary amount for each ticket delivered and finally to actuate said gear and uncouple said driving shaft from the ticket issuing unit, a plurality of selector keys each operable to unlock said ratchet member, differential abutment mechanism controlled by said keys and operable to limit the extent of movement of said ratchet member by said yielding control an amount equal to one or a plurality of said unitary amounts in accordance with the key operated, and an operative connection between the motor switch and the gear mechanism operable to close said switch after the driving shaft is coupled by the gear mechanism and to open the switch when the number of tickets corresponding to the key selected have been delivered.

27. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, manually operable selector devices adapted to control the circuit of said motor and couple the same in driving relationship to said Geneva mechanism to deliver one or a plurality of tickets solely in accordance with the manually operable device selected, and yielding means operable to receive a plurality of tickets so delivered and maintain them in frictional engagement with one another with the forward ends thereof relatively displaced and extending exteriorly of the machine.

28. A ticket issuing machine which comprises in combination a rotary feed drum provided with peripheral pins adapted to extend through holes formed in a ticket strip whereby rotation of said drum feeds said strip, a Geneva mechanism operatively connected to said drum and operable upon each actuation to rotate said drum and feed one ticket from the machine, an electric motor, a plurality of selector keys adapted to control the circuit of said motor and couple the same in driving relationship to said Geneva mechanism to deliver one or a plurality of tickets solely in accordance with the key selected and yielding means operable to receive a plurality of tickets so delivered and maintain them in frictional engagement with one another with the forward ends thereof relatively displaced and extending exteriorly of the machine.
